UNITED STATES PATENT OFFICE.

OTTO GOTTSCHALK, OF DRESDEN, GERMANY.

SPRINKLING STOPPER.

Application filed August 11, 1924. Serial No. 731,511.

To all whom it may concern:

Be it known that I, OTTO GOTTSCHALK, a citizen of the German Republic, residing at 69 Kaitzerstrasse, Dresden, Germany, have invented certain new and useful Improvements in Sprinkling Stoppers, of which the following is a specification.

The subject of this invention is a sprinkling stopper for bottles and the like, in which a cover is rotatably mounted over a cap having an eccentric orifice and fixed to the neck of the bottle.

According to the invention a closing member having an oblique bore is located on the cap so as to be coaxial and rotatable with the cover, the said closing member being kept in close contact with the cap by means of a leaf spring, which is placed on it and finds an abutment against the cover.

20 In the accompanying drawing a constructional example of the invention is shown,

Figures 1 to 4 showing the cap, the cover, the closing member and the leaf spring in section and in plan view and

25 Figure 5 showing the stopper in section.

The new stopper comprises four parts, a cap *a*, a cover *l*, a closing member *f* and a leaf spring *o*. The stop of the cap *a* (Fig. 1), which is fixed on the neck of the bottle, is dished out centrally at *b*, the outer surface *c* of the dished out part being made exactly even and provided with an aperture *d*, which is slightly eccentric. At the edge of the cap *a* is a bead *e*.

35 On the surface *c* of the cap rests the closing member *f* (Fig. 3) and the surface with which it rests on the cap is also exactly even. The closing member *f* is pierced by a hole *h*, which extends obliquely upwards from the hole *d* in the cap and has its outlet in the axis of the closing member. This part of the closing member terminates in a square head *i*, which engages in a corresponding square hole *k* in the cover *l* (Fig. 2). The bent over rim *m* of the cover engages under the bead *e* of the cap *a*. By this means the cover *l* together with the closing member *f* can be turned about the central axis, the bottle being opened and closed according to the position of the bore *h* relative to the hole *d*.

In order to obtain a tight closure between the surfaces *c* and *g*, a leaf spring *o* (Fig. 4) provided with a suitable square hole *n* is placed on the square head *i* of the closing member *f*, the unsupported ends of the said spring resting against the inside of the cover *l* and thereby holding the closing member *f* with a constant uniform pressure against the top of the cap *a*. By this means a perfectly tight closure is ensured.

What I claim is:—

1. A stopper for sprinkling vessels comprising in combination a cap capable of being fixed to the neck of the vessel, an eccentric hole in the top of the cap, a rotatable cover surrounding the said cap, a closing member on the top of the cap so as to be coaxial with the rotatable cover and rotatable with the same, a bore in the closing member, the lower end of which bore is at the same distance from the axis of rotation as the eccentric hole in the top of the cap, and a resilient member between the top of the closing member and the underside of the top of the cover for holding the bottom surface of the closing member in close contact with the top surface of the cap, as set forth. 75

2. A stopper for sprinkling vessels comprising in combination a cap capable of being fixed to the neck of the vessel, an eccentric hole in the top of the cap, a rotatable cover surrounding the said cap, a closing member on the top of the cap so as to be coaxial with the rotatable cover and rotatable with the same, an oblique bore in the closing member, the lower end of which bore is at the same distance from the axis of rotation as the eccentric hole in the top of the cap, and a resilient member between the top of the closing member and the underside of the top of the cover for holding the bottom surface of the closing member in close contact with the top surface of the cap, as set forth. 85

3. A stopper for sprinkling vessels comprising in combination a cap capable of being fixed to the neck of the vessel, an upwardly dished flat portion in the top of the cap, an eccentric hole in the said flat portion, a rotatable cover surrounding the said cap, a closing member on the top of the cap so as to be coaxial with the rotatable cover and

rotatable with the same, a bore in the closing member, the lower end of which bore is at the same distance from the axis of rotation as the eccentric hole in the top of the cap, and a resilient member between the top of the closing member and the underside of the top of the cover for holding the bottom

surface of the closing member in close contact with the top surface of the cap, as set forth.

10

In testimony whereof I have signed my name to this specification.

OTTO GOTTSCHALK.
